UNITED STATES PATENT OFFICE.

WILLIAM H. BARBER, OF WARD, OHIO.

AUTOMATIC REGISTERING-MACHINE.

SPECIFICATION forming part of Letters Patent No. 329,120, dated October 27, 1885.

Application filed June 1, 1885. Serial No. 167,322. (No model.)

To all whom it may concern:

Be it known that I, WILLIAM H. BARBER, of Ward, in the county of Washington and State of Ohio, have invented certain new and useful Improvements in Automatic Registering-Machines, of which the following is a full, clear, and exact description.

This invention relates to a machine for enumerating or registering automatically; and it consists in the mechanism hereinafter described, constructed and arranged so that the enumerating-tape may be transferred back and forth upon separate and independent drums, first upon one drum and then upon the other, and transferring-rollers having an intermittent movement simultaneously first in one direction and then in the opposite direction to carry the enumerating-tape between them a certain fixed or given distance at every intermittent movement thereof forward or back independent of the drums to receive and hold the tape thereon.

Reference is to be had to the accompanying drawings, forming part of this specification, in which similar letters of reference indicate corresponding parts in all the figures.

Figure 1 represents a vertical section through the line $x x$ of Fig. 2 of a box to receive and hold the operating mechanism; Fig. 2, a cross-section of the box, and showing a top view of the mechanism therein, together with a fragment of the enumerating or registering tape; Fig. 3, a front view representing the open space in the box before which the numbers on the tape are presented consecutively one after another to be read, and the slide for obscuring alternately the columns of figures thereon, first one column and then the other, as may be required.

A in the accompanying drawings represents a suitable box, in which the enumerating or registering mechanism is inclosed and operates.

B B are two drums mounted upon shafts C C, supported in suitable bearings in the box A, to receive and hold an enumerating-tape, C', which is to be wound alternately thereon—first upon one drum and then upon the other. Around the shafts of these drums B B are coiled springs D D, one end of each spring being fastened to the shaft, which it surrounds, and the other end fastened to the box A, as

shown, so that as the enumerating-tape C' is drawn from the drum upon which it is wound the opposite or corresponding drum will continue to wind it thereon until the whole length of the tape is transferred from one drum to the other, in which operation the coiled springs D D serve to revolve the drums alternately, the springs being wound around the shafts by the movement of the enumerating-tape back and forth.

In order that the enumerating-tape C' shall move intermittently a certain fixed or given distance at each movement independently of the drums B B, to present the numbers thereon consecutively and regularly one after another before an opening, G, Fig. 3, in the side of the box A, it is passed between two intermediate transfer-rollers, H H, whose surfaces 7c may be covered with rubber V, or other suitable material to obtain sufficient friction to embrace and move the tape positively a given distance without slipping and without injury thereto.

In order to overcome the tension exerted by the springs D at any stage of the transfer of the tape from one drum to the other, the tape is to be held between the transfer-rollers H H with sufficient frictional force so that they 80 will not be moved by the action of the springs D, and will only move when a force beyond that of the springs be exerted by means of the pawls J J' to overcome the friction of the rollers. If preferred, a double check-pawl may 85 be employed to prevent any retrograde movement of the transfer-rollers. This double check-pawl may be constructed and arranged to operate the same as the double push-and-pull pawls J J', and shifted by hand to take 90 into the notched wheels alternately to permit the transfer-rollers to revolve back and forth and to operate in unison with the pawls J J' to hold the rollers H H, so that they shall revolve only when moved by the pawls J J', and 95 to obtain the required intermittent movement of the enumerating-tape these transfer-rollers H H are provided with ratchet-wheels I I, secured to their shafts, as shown in dotted lines in Fig. 1, and are operated by a double pawl, 100 J J', first in one direction and then in the opposite direction thereto.

The double pawl J J' is pivoted at m to a vibrating bar, K, in such relative position to

the transfer-rollers H H that the upper push-pawl, J, which is heavier than the lower hooked pawl, J', will remain by its own weight engaged with the upper ratchet-wheel, and by 5 its action move the tape in one direction, and when it is desired to reverse the direction of the movement of the tape the upper pawl, J, is disengaged by hand or in any other convenient manner from its ratchet-wheel and, passing beyond 10 a perpendicular with its pivot m, will drop back, and the hooked pawl J' will be held engaged with the ratchet-wheel of the lower roller, thus reversing the direction of the movement of the enumerating-tape, as required.

15 From the opposite end of this vibrating bar K extends a connecting-rod, L, downward to connect with the platform of a weighing-scale by which to vibrate the bar intermittently to impart a correspondingly intermittent movement to the transfer-rollers H H through the 20 pawls J J' and ratchet-wheels I.

Upon one side of this enumerating-tape C' two columns of figures are arranged to enumerate the number of bags or other articles being weighed, one after another. These columns commencing with figure 1, are arranged to enumerate in opposite directions side by side, so that as the tape is transferred alternately from one drum to the other the columns may be 25 read alternately first one column and then the other, according to the direction of movement of the tape; and to prevent error which might occur by reading the wrong column, a slide, N, over the opening G, Fig. 3, slides back and forth to obscure, alternately, first one 30 column and then the other, as the movement of the tape requires.

In order to present the tape C' over the opening G in the box when wound upon the 35 upper drum, and direct it to the lower drum, to be wound thereon, a loose guide-roller, W, is arranged, over which the tape is passed from the transfer-rollers H H, and thence to the lower drum, as shown. Two pins, O O, are placed one above and one below the vibrating 40 bar K, so as to restrict its movement up and down in order that the ratchet-wheels shall be turned a certain given distance at each vibration of the bar K by means of the pawls 45 thereon.

The operation of this enumerating mechanism may be described briefly as follows: The 50 rod L being connected with a weighing-scale, and as each bag or article is placed thereon and weighed the bar K is vibrated the distance 55 between the stop-pins O O, so as to move the ratchet-wheels one or more notches, as the

case may be, to revolve the transfer-rollers H H and carry the tape forward, so as to present the numbers thereon consecutively, one after another, to the opening G, to be read, and as the tape is drawn intermittently from one drum by means of the transfer-rollers H H, the opposite drum, by means of its spring, will take up the tape as it is presented until 60 its entire length has been transferred from one drum to the other. The double pawl is now changed from one ratchet-wheel to the other, as shown in dotted lines, Fig. 1, thereby reversing the movement of the tape, which 65 commences to be transferred back to the empty drum, and so on the operation of transferring the tape from one drum to the other may be repeated at pleasure. At each transfer of the 70 tape the slide N is also shifted, so as to expose the column of numbers to correspond 75 with the direction of movement of the tape.

It is evident that this enumerating mechanism may be operated in connection with any of the well-known bagging and weighing devices, threshing or winnowing machines, or grain-elevators, without additional contrivances and without departing from my invention.

Having thus described my invention, what 85 I claim as new, and desire to secure by Letters Patent, is—

1. In a machine for enumerating or registering, in combination with the tape C' and drums B B, the intermediate transfer-rollers, 90 H H, ratchet-wheels I I thereon, pawls J J', and lever K, whereby articles may be enumerated consecutively, one after the other, as described.

2. In a machine for enumerating or registering, in combination with the tape C', having two columns of numerals thereon, and drums B B, the intermediate transfer-rollers, H H, ratchet-wheels I I, secured thereto, pawls J J', and lever K, whereby the tape may 100 be transferred alternately from one drum to the other, as described.

3. In a machine for enumerating or registering, in combination with the tape C', having two columns of numerals thereon, drums 105 B B, intermediate transfer-rollers, H H, and ratchet-wheels I I, the pawls J J' and lever K, to reverse the movement of the tape C', so as to enumerate in both directions, constructed and arranged as described.

WILLIAM H. BARBER.
